UNITED STATES PATENT OFFICE.

ERNEST CANTELO WHITE, OF NEW YORK, N. Y., ASSIGNOR TO ELECTRIC OUTLET COMPANY, INC., OF NEW YORK, N. Y., A CORPORATION OF NEW YORK.

DESIGN FOR AN ELECTRICAL RECEPTACLE.

58,518.

Specification for Design.

Patented July 26, 1921.

Application filed January 14, 1921. Serial No. 437,364. Term of patent 14 years.

To all whom it may concern:

Be it known that I, ERNEST CANTELO WHITE, a citizen of the United States, residing in the borough of the Bronx of the city of New York, in the State of New York, have invented a new, original, and ornamental Design for an Electrical Receptacle, of which the following is a specification, reference being had to the accompanying drawing, forming a part hereof.

The figure is a plan view of an electrical receptacle showing the new design.

I claim—

The ornamental design of an electrical receptacle, as shown.

This specification signed this third day of January, A. D. 1921.

ERNEST CANTELO WHITE.
